UNITED STATES PATENT OFFICE.

WILLIAM F. PAULETT, OF SCOTTSVILLE, VIRGINIA.

ADJUSTABLE TRESTLE.

Application filed April 28, 1926. Serial No. 105,254.

This invention relates to trestles for use by plasterers, wall paperers, carpenters, and like workmen for supporting the end of a platform or for use when in moderately elevated conditions to support the workmen directly thereon without requiring a pair of the trestles between which the usual platform board is arranged.

The primary object of the invention is to substantially improve and simplify over trestles of this character and to the attainment of this end, an extremely simple, but yet highly novel construction is employed in order that the trestle may be elevated to great height or lowered as desired, and that may be readily knocked down for transportation or storage.

An additional object of the invention is to provide a trestle wherein an improved form of clamp is employed to maintain the adjustably associated parts rigidly interconnected and without any liability of the same slipping which is the main disadvantage with trestles of this general character.

Other objects will become apparent as the nature of the invention is better understood, the same comprising the novel form, combination, and arrangement of parts herein-after more fully described, shown in the accompanying drawings and claimed.

In the drawings wherein like reference characters indicate corresponding parts throughout the various views:

Figure 1 is a side elevation of my improved trestle, in partly elevated condition.

Figure 2 is an end elevation thereof.

Figure 3 is an enlarged fragmentary vertical section taken substantially upon the line 3—3 of Figure 2 for more clearly disclosing the interconnection of certain parts of the trestle.

Figure 4 is a detail longitudinal section taken substantially upon the line 4—4 of Figure 1 for disclosing another form of clamp between certain of the vertically adjustable interconnected members, and

Figure 5 is a detail longitudinal section taken substantially upon the line 5—5 of Figure 1 for bringing out more clearly certain structural elements of the trestle.

Now having particular reference to the drawings, my novel trestle constitutes the provision of a horse-like unit designated generally 5 consisting of a cross beam 6 upon the opposite faces and adjacent the opposite ends of which are attached the offset

ends of outwardly converging legs 7, the connection between the legs and the beam at the opposite ends thereof consisting of an elongated bolt 8 threaded at one end and 60 threaded at the opposite end for the reception of a handle clamping nut 9 in order that the bolt may be readily loosened to permit the leg to be swung inwardly of the beam if desired, or to be entirely detached 65 therefrom in an expeditious manner.

The legs 7 at each end of the beam 6 are interconnected by cross bars 10—10 arranged upon the opposite sides thereof, Figure 5, and secured to the legs and to each other by 70 bolt and nut connections 11. Arranged upon the outer sides of the legs 7—7 are supplemental extension legs 12 guided between the ends of the bars 10—10 which bars project slightly outwardly of the legs 7 as clearly disclosed in Figure 5. Said supplemental extension legs 12 are formed throughout the major portion of their length with slots 13 through which engage the forward threaded ends of shouldered and headed bolts 14 arranged rigidly within the lower end of each leg 7, Figures 2, 4, and 5. Arranged over the outer end of each bolt 14 that projects through the slot 13 of the complementary extension leg 12 is a rigid metallic clamp 80 plate 15, the opposite side edges of which are flanged inwardly as at 16—16 for engagement upon the sides of the respective extension 12 to prevent the turning of the plate upon the bolt. Arranged upon the 90 end of each bolt 14 outwardly of the respective plates 15 is a handle clamping nut 17 to permit the extension legs 12 to be rigidly secured with respect to the complementary beam legs 7. Through the provision of the 95 extension legs 12 the horse like unit 5 may be raised or lowered to the desired height and also the same may be arranged in a horizontal manner regardless of the inclination of the floor or other support upon which 100 the trestle is disposed, this by extending the legs in a predetermined manner with respect to the legs 7 of the horse. By the use of the particular form of clamp detailed in Figure 4, it will be readily appreciated that 105 the handle nut may be turned inwardly upon the bolt to such an extent as to absolutely rigidly connect the legs 12 with the legs 7 and this without any liability of splitting either of such legs.

Interconnecting the bars 10—10 between the legs 7 at each end of the beam 6 is a cross

beam 18, the opposite ends of which are beveled at their under side as clearly disclosed in Figure 3 in order that flush engagement of the beam will be had with respect to the bars 10—10. Each end of the beam 18 has rigidly mounted therein a depending headed and threaded bolt 19 that extends between the bars 10—10 beneath which a clamp plate 20 is arranged upon the threaded end of the bolt. Intermediate the ends of each clamp plate and upon the top side thereof is a boss 21 that extends between the bars to prevent the turning of the plate upon the bolt.

Beneath each clamp plate and arranged upon the threaded end of the bolt 19 is a handle nut 22, for an obvious purpose.

Interconnecting the beams 6 and 18 respectively, is a diagonally extending bar 23 that is pivotally connected at one end as at 24 to the beam 6 and detachably connected at its opposite end as at 25 to the beam 18 in order that the same may be readily disconnected from the beam 18 and swung upwardly into position alongside the beam 6 after the trestle has been knocked down. Likewise the legs 7—7 at opposite ends of the beam 6 may be swung inwardly with respect thereto after the beam 18 has been detached from the leg connecting bars 10—10.

The trestle further constitutes the provision of an additional beam 27 in horizontal alignment with the other beams 6 and 18 and in position above the beam 6. Depending from said beam 27 intermediate the opposite ends thereof are detachable relatively elongated legs 28—28 that extend downwardly alongside the beams 6 and 18, Figures 1, 2, and 5.

The legs 28—28 are slotted throughout the major portion of their length as at 29 in order that a slidable interconnection may be had between the legs and the beams 6 and 18 through the medium of connections identical to that disclosed in the detailed view, Figure 4. For detachable arrangement upon the top side of the beam 27 is a workman supporting platform board 30 in order that a single trestle may be employed for the support of a workman when the elevation required is not greater than that of the length of the legs 28—28.

It will thus be seen that through the pro-

vision of a trestle of this character either one of the three beams 6, 18, or 27 may be employed for supporting the opposite ends of a platform for thus providing at all times three elevations without requiring the adjustment of the trestle for securing such elevation. However, it is readily obvious that the trestle 6 may be raised or lowered whenever desired, as also may be the beam 27 thus permitting a great height to be obtained, and this without impairing the supporting qualities of the trestle.

Although I have herein shown and described the invention as consisting of certain detail elements of construction, it is nevertheless to be understood that departures may be had therefrom without effecting the spirit and scope of the appended claims.

Having thus described the invention, what I claim as new and desire to secure by Letters Patent is:—

1. In an adjustable trestle structure of the class described, a supporting horse comprising a horizontal top beam, pairs of main legs connected to the end portions of said beam and depending therefrom in spaced diverging relation, cross pieces connected with the intermediate portions of the main legs, the ends of said cross pieces extending beyond said legs, and auxiliary extension legs adjustably connected with the main legs and slidably confined between the extending end portions of the cross pieces.

2. In an adjustable trestle of the class described, a horse comprising a horizontal top beam, downwardly diverging legs at the ends of said beam, spaced cross pieces secured to each pair of legs, a second beam disposed horizontally beneath the top beam and across the top of said cross pieces, a clamping plate disposed transversely across the bottom of each pair of spaced cross pieces, an upstanding boss on each clamping plate and disposed between each pair of spaced cross pieces, bolts extending through the ends of the second beam and through the bosses and intermediate portions of the respective clamping plates, and a nut threaded on the lower end of each bolt.

In testimony whereof I affix my signature.

WILLIAM E. PAULETT.
